UNITED STATES PATENT OFFICE

167,933

INSTRUMENT FOR MEASURING HUMIDITY
AND TEMPERATURE

Donal G. Erskine, Jr., Baltimore County, Md., assignor to Bendix Aviation Corporation, Baltimore, Md., a corporation of Delaware

Application April 29, 1952, Serial No. 19,519

Term of patent 14 years

(Cl. D52—7)

To all whom it may concern:

Be it known that I, Donal G. Erskine, Jr., a citizen of the United States, residing in the county of Baltimore, in the State of Maryland, have invented a new, original, and ornamental Design for an Instrument for Measuring Humidity and Temperature, of which the following is a specification, reference being had to the accompanying drawings, forming a part hereof.

In the drawing:

Figure 1 is a perspective view of an instrument for measuring humidity and temperature, showing my new design; and

Figure 2 is a side elevational view of the instrument shown in Figure 1; and

Figure 3 is a plan view of the instrument shown in Figure 1; and

Figure 4 is a front elevational view of the instrument shown in Figure 1.

The side of the instrument not disclosed in Figure 1 is substantially the same in appearance as the side shown.

I claim:

The ornamental design for an instrument for measuring humidity and temperature, as shown and described.

DONAL G. ERSKINE, JR.
